EDWARD KIRBY BOTTLE, OF ELMIRA, NEW YORK, ASSIGNOR TO AMERICAN SALES BOOK COMPANY, LIMITED, OF TORONTO, ONTARIO, CANADA, A CORPORATION OF ONTARIO, CANADA.

MANIFOLDING SALES-BOOK

1,295,104.

Specification of Letters Patent. Patented Feb. 25, 1919

Application filed September 18, 1916. Serial No. 120,693.

To all whom it may concern:

Be it known that I, EDWARD KIRBY BOTTLE, a citizen of the United States, residing at Elmira, in the county of Chemung and State of New York, have invented certain new and useful Improvements in Manifolding Sales-Books, of which the following is a full, clear, and exact description, such as will enable others skilled in the art to which it appertains to make and use the same.

This invention relates to salesbooks and, with respect to more specific features, to manifolding sales-books adapted to provide triplicate copies.

One object of the invention is the provision of an efficient manifolding salesbook which may be quickly operated and in which is provided a receptacle or pocket for the reception of copies to be retained in the book, the construction being such that the copies may be introduced into the receptacle by a simple manipulation of the leaf and without necessitating any substantial movement of the pads.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings forming part of this specification, wherein similar reference characters refer to similar views;

Figure 1 is a perspective view of an embodiment of the invention;

Fig. 2 is a longitudinal section through Fig. 1, with one of the triplicate leaves drawn partway into the pocket.

Referring now more specifically to the drawings, the numeral 1 indicates a supporting element, in the present instance an element which operates both as a leaf support and as a pad support. The numeral 2 indicates another supporting element, and in the present embodiment it is adapted to support a paragon pad 3 composed of original and duplicate leaves, the duplicates being bound in a stud 4 and removably held on the supporting element 2 by means of a clamp 5. The numeral 6 indicates a double faced carbon sheet bound with the leaves of the paragon pad in the usual manner. The support-

ing element 2 is rigidly connected at one side 7 to and overhangs the supporting element 1, its other side 8 being free, so that the element 2 is superposed relative to the element 1 and is spaced therefrom, whereby a pocket or leaf receptacle is formed between the supporting elements 1 and 2, this receptacle lying beneath the pad 3 and being open on three adjacent sides; that is on all sides except the side 7. The supporting element 1 at one end, as 9, extends beyond the adjacent edge of the element 2, and is preferably bent upwardly toward the plane of the support 2, and has attached to it by means of a clamp 10 a pad 11 of triplicate leaves preferably of tissue. The leaves of the pads 11 and 3 are adapted to over-lap, those of the triplicate pad being adapted to over-lie the original and duplicate pad, and as well over-lie the extended portion 9 of the supporting element 1. In this wise it will be seen that the pads are so related that the bound end of the triplicate pad extends beyond the edge of the original and duplicate pad, and is so disposed that the successive leaves of the triplicate pad may be interposed between the original leaf of pad 3 and the carbon or transfer sheet 6, as illustrated in Fig. 1 when a record is to be made. When the pads are set up in the relationship illustrated in the drawings, it will be observed that they are connected to their respective supports along separate lines, and that the open end 12, of the receptacle adjacent the triplicate pad provides a passageway opposite the extended portion of both the triplicate pad and the support 1, which passageway communicates with the pocket or space between the elements 1 and 2, such passageway opening upwardly across the inner edge 13 of the support 2, this passageway being adjacent the rigid side 7 and between the lines of connection of the pads to the support.

The support comprising the elements 1 and 2 may be conveniently made of thin metal bent into U-shape, being covered with leather or other material to finish the same. The numeral 14 indicates a cover, shown partly broken away, which may be connected to the aforementioned support by means of a flexible hinge 15, so that when the book is not in use the pad 11 may be folded down onto the pad 3 and the cover 14 closed.

In operation the triplicate pad is thrown back; the original leaf is drawn from be-

neath the carbon sheet, and the lower leaf of the triplicate pad is moved down into position between the carbon sheet and the original leaf. A record made on the original leaf 5 will be copied in reverse on the triplicate leaf and positively on the duplicate leaf. The record having been made, a tool such as a pencil may be pressed against the portion of the triplicate leaf overlying the extension 10 9, the pencil being moved downwardly past the edge 13 of the support 2 and then inwardly or toward the operator, through the inner end of the pocket or leaf receptacle, thus sweeping the triplicate leaf into the receptacle where it may be retained. In the present embodiment the outer end 16, of the receptacle is open so that the tool may be moved completely out of the receptacle by movement toward the operator. In Fig. 1, 15 a pencil 17 is shown in position wiping a leaf into the receptacle.

While the connection between the supporting elements 1 and 2 has been described as rigid, it is to be understood that it is not necessarily of an absolutely unyielding nature, but need be only sufficiently rigid to properly space the pad support 2 from the support 1. Obviously a hinge connection might be employed if it were of a character 25 to accomplish the result referred to.

It may be found that after continued use the element 2 takes a set more or less toward the element 1, so that the operation of transferring the triplicate leaf into the receptacle 30 5 may not be so readily accomplished. The numerals 18 indicate struts pivotally connected to the support 2 at 19, the lower ends of said struts being adapted to contact with the face of the supporting element 1, these 35 struts serving to hold the free edge of the support 2 at a distance from the support 1, but not interfering with the passage of the tool 17, through the receptacle in the operation described.

40 Thus by the above described construction are accomplished, among others, the objects heretofore referred to.

As many changes could be made in the above construction and many apparently 45 widely different embodiments of this invention could be made without departing from the scope thereof, it is intended that all matter contained in the above description or shown in the accompanying drawings shall 50 be interpreted as illustrative and not in a limiting sense.

It is also to be understood that the language used in the following claims is intended to cover all of the generic and specific 55 features of the invention herein de-

scribed and all statements of the scope of the invention, which, as a matter of language, might be said to fall therebetween.

Having described my invention, what I claim as new and desire to secure by Letters Patent is:

1. A manifolding device comprising in combination, a support, two pads so connected to said support that the leaves of the two pads will overlap, one pad extending 70 beyond the edge of the other, said support comprising a receptacle beneath one of said pads and a passageway opposite said extended portion communicating with said receptacle, said receptacle being open on a side 75 adjacent said passageway and a side opposite said passageway.

2. A manifolding device comprising in combination, a support, and two pads connected to said support along separate lines, 80 said support comprising a receptacle beneath one of said pads and a passageway between said lines communicating with said receptacle, said receptacle being open on a side adjacent said passageway and a side opposite said passageway. 85

3. A manifolding device comprising in combination, a support comprising superposed pad-supporting elements spaced apart and rigidly connected at one side, the opposite side being free, one of said elements extending beyond the edge of the other adjacent said first mentioned side, pads on said elements, respectively, one pad being positioned to have its leaves overlie the other 90 pad and the extended portion of the supporting element, there being a passageway opposite said extended portion leading to the space between said elements. 95

4. A manifolding device comprising, in combination, a leaf support, a pad support overhanging said leaf support and connected thereto at one side, its other side being free, and struts connected to one of said supports adapted to hold said pad support 100 spaced from said leaf support.

5. A manifolding device comprising, in combination, a leaf support, a pad support overhanging said leaf support and connected thereto at one side, its other side being free, 110 and pivoted struts connected to one of said supports adapted to hold said pad support spaced from said leaf support.

In testimony whereof I affix my signature, in the presence of two witnesses.

EDWARD KIRBY BOTTLE.
